CLAËS G. HALL, OF WASHINGTON, DISTRICT OF COLUMBIA.

UTERINE SUPPORT.

1,170,250.

Specification of Letters Patent.

Patented Feb. 1, 1916.

Application filed October 12, 1915. Serial No. 55,422.

To all whom it may concern:

Be it known that I, CLAËS G. HALL, a citizen of the United States, and a resident of Washington, District of Columbia, have 5 invented a new and useful Improvement in Uterine Supports, of which the following is a specification.

My invention is an improvement in uterine supports of the character designated, 10 and the invention has for its object to provide a support of the character specified, that may be worn with comfort and convenience, that may be adjusted to suit varying conditions, which will be unaffected by discharges of any character, and which may be easily removed and replaced, and which will afford a perfect support.

In the drawings: Figure 1 is a top plan view of the improved support, Fig. 2 is a 20 section on the line 2—2 of Fig. 1, Fig. 3 is a vertical section through the supporting cup showing its mounting, and Fig. 4 is a perspective view of the adjusting sleeve.

In the present embodiment of the invention, 25 a flexible supporting member is provided, comprising upper and lower sheets 1 and 2 of soft flexible material, as for instance, for the sheet 2 cloth and for the sheet 1 chamois-skin or the like, the first-named sheet being rectangular, while the last-named is of smaller size and of irregular form, as shown.

Suitable supporting straps 3 are provided at one side of the supporting member, 35 the said straps being of tape or the like, and other straps 4 are provided at the opposite side. The straps 3 extend approximately parallel in spaced relation as shown, while the straps 4 diverge from each other, 40 and other straps 5' are connected with the supporting member at the outer sides of the straps 4. These straps 3, 4 and 5' are connected with a suitable belt in any desired or convenient manner, and the supporting 45 element proper is connected with the supporting member 1—2.

The support proper comprises a shallow cup-shaped receiver 5, in the form of a hollow spherical segment, and having at its 50 center a socket 6. This socket 6 is adapted to receive a ball 7 on one end of a rod 8 of suitable length and cross section. The rod and the receiver 5 as well as the socket 6 are of non corrosive material, as for instance, silver of sufficient purity to prevent corrosive action from the discharges.

The socket 6 is in the form of a cup in the first instance, and after the ball 7 is inserted, the free edge of the socket is upset or bent inwardly as indicated to prevent 60 disengagement of the ball, while at the same time permitting a limited swinging movement of the receiver with respect to the rod.

The rod is adjustably connected with the flexible member 1—2, by means of a sleeve 65 9, the said sleeve being rigidly connected with the flexible supporting member at the center thereof. This sleeve is provided with a radial internally threaded nipple 10, and a set screw 11 is threaded through the nipple, 70 the set screw extending into the interior of the sleeve and engaging the rod 8 to hold the rod in adjusted position.

The sleeve is provided at its upper end with oppositely extending eyes 12, and these 75 eyes are arranged between the sheets 1 and 2 of the flexible member as shown, and are secured to the sheets by means of stitching or the like, the stitches being passed through the eyes. Thus while the sleeve is rigid with 80 the flexible supporting member so far as vertical movement of the sleeve with respect to the said member is concerned, yet it may move laterally at its free end to prevent damage to the flexible member or to the 85 sleeve by swinging movement of the rod. The sheet 2 is of smaller size than the sheet 1, and is superposed on the under face of the sheet 1 at the center thereof, and is secured thereto and to the straps 3—4—5' by 90 a double row of stitching 13. The double row of stitching 13 outlines the edge of the sheet 2, and this stitching is passed through the sheet 1 and through the ends of the straps 3—4—5'. 95

It will be noted that at one edge of the sheet 1 the sheet 2 is pointed as shown, the apex being between the straps 3. The sheet 1 is of such length that when the support is in place, the free ends of the sheet will depend on each side of the lower end of the rod 8 to protect the wearer against injury or chafing by the lower end of the rod. By arranging the sheet 2 at the center of sheet 1, a reasonable rigid supporting member is 100 provided for the sleeve 9, and depending guards or shields for preventing chafing by the end of the rod. The sheet 1 may be washed when necessary, and since it is of leather it will not absorb discharges and become foul. 105

The cup-shaped receiver has a limited an-

gular movement with respect to the rod because of the universal joint connection, consisting of the ball and socket 6 and 7, and since this element as well as the rod 8 is of 5 silver they will not be injured by the discharges. Preferably the straps 5' have buckles or snap fasteners, not shown, at their ends for connection with tapes to connect the said straps with the supporting belt, and 10 tapes 14 may be secured to the straps 4; the said tapes may have buckles for connection with the straps. The elements 4 and 5' are in fact tabs for connection with supporting straps, and these straps as well as the straps 15 3, may be of elastic material.

In operation, the support 1—2 is arranged in position, being supported by a suitable belt and loosening the set screw 11, the wearer will adjust the rod 8 to the proper 20 height to provide for the necessary support. Whenever it is desired to remove the support the set screw may be loosened and the rod may be withdrawn, after which the support may be loosened from the belt. The support 25 is intended to be worn during the time that the user is on her feet and moving around, and it will be removed at other times. Because of the fact that the metal parts

5—6—8 are of silver they will be always clean, and there will be no danger from the 30 insertion of septic matter.

The device while simple is efficient, and because of the simplicity of construction and the few parts it may be manufactured at a reasonable cost and will not easily get out 35 of order.

I claim:—

A support of the character specified, comprising a pad consisting of a sheet of chamois-skin or the like, having superposed 40 on the under face and at the center thereof a sheet of fibrous material, supporting tabs having their ends received between the sheets and securing means passing through the sheets and the tabs, a sleeve held at the center of the pad and extending through the same, a rod of silver slidable in the sleeve, a receiving cup of silver having a ball and socket joint connection with the upper end of the rod, a set screw threaded through the sheet for holding the rod in adjusted position, the end of the flexible pad depending on each side of the rod to prevent chafing of the lower end of the rod. 45 50
